UNITED STATES PATENT OFFICE.

JAMES CAVANAGH, OF BOSTON, MASSACHUSETTS, ASSIGNOR TO UNITED SHOE MACHINERY COMPANY, OF PATERSON, NEW JERSEY, A CORPORATION OF NEW JERSEY.

WELT-LAYING MACHINE.

1,161,843.

Specification of Letters Patent. Patented Nov. 30, 1915.

Application filed November 20, 1911. Serial No. 661,211.

To all whom it may concern:

Be it known that I, JAMES CAVANAGH, a citizen of the United States, residing at Boston, in the county of Suffolk and State 5 of Massachusetts, have invented certain Improvements in Welt-Laying Machines, of which the following description, in connection with the accompanying drawings, is a specification, like reference characters on 10 the drawings indicating like parts in the several figures.

This invention relates to welt-laying machines and is herein shown and described as embodied in new and improved mechanism 15 for supporting and pressing a welt or other marginally projecting portion of a shoe against the margin of the sole which extends beyond the last in opposition to the pressure applied to the outer face of the 20 sole in the sole laying operation. It is to be understood, however, that the invention may be used in other machines where a similar structure or function is desired. In the present instance the invention is shown 25 as embodied in a sole laying machine of the type disclosed in the United States patent to Holland, 362,447, and in that to Davenport, 781,636, which is in extensive use for laying the outsoles in welt shoes 30 and to which patents reference may be had for a detailed description of such parts of the machine as are not fully described herein.

In the process of making welt shoes, after 35 the welt is attached and the inseam trimmed, a filling of cork and cement is placed upon the insole to bring it up level with the inseam. Cement is then applied to the filling and to the welt and also to the 40 inner face of the outsole. The outsole is positioned upon the shoe and the shoe placed in the sole laying machine which supports the shoe at the heel and toe portions and forces a molded pad against the outer face 45 of the sole to shape the sole and press it firmly in contact with the shoe and hold it in position until the cement has caused the outsole to adhere to the shoe. It is found in practice, however, that there is often im- 50 perfect adhesion of the welt to the margin of the outsole especially when the welt is of light stock or is inadequately beaten, and that the welt has therefore a tendency to curl or twist away from the sole. This tend-

ency is particularly noticeable at those portions of the periphery of the forepart of the shoe having the greatest outward curvature, that is, at the toe and just to the rear of the ball portion. In sewing on a welt around a curved portion of the shoe the 55 outer margin of the welt is placed under tension and as a result of this the welt has a strong tendency to turn upwardly toward the shoe upper. This tendency is further accentuated by the angle formed in the material of the welt along the line where it is attached to the margin of the upper and the between-substance of the insole. This lack of adhesion between the welt and the outsole 60 is due also to a partial return of the outsole 65 to its original flat condition after the removal of the shaping pressure of the pad thereupon. The tendency of the welt to curl upwardly away from the margin of the outsole is partially, but usually not entirely, 70 overcome by the operation of welt beating. It is of course highly desirable that all tendency of the welt to twist or curl away from the sole be overcome during the sole laying 75 operation so that the welt will adhere properly to the sole margin throughout its extent. As a result of the lack of adhesion between the welt and the margin of the outsole and their consequent separation, the 80 cement between them is exposed to the air 85 and its hardening accelerated, and as often some time elapses between the operation of sole laying and that of sewing on the outsole 90 it may happen that the cement has become so hard as to interfere seriously with making a close connection between the welt and the margin of the outsole in the outsole stitching operation.

As a feature of the present invention, 95 novel means associated with a toe block is provided which extends around the forepart of the shoe and clamps the welt against the outstanding edge of the outsole. This welt pressing means may be continuous as shown, or may be in a number of sections 100 suitably supported. The part of the welt presser which engages the welt is preferably made resilient or yielding, so that as pressure is applied thereto all parts of the welt 105 will be engaged and held against the outsole. In case the welt presser is made of such material as soft rubber it may be desirable to back it up by more rigid material, such for

example as a plate of spring steel or even one of more rigid material placed upon the welt presser and through which pressure is applied thereto. The yielding and resilient characteristics of the presser are of importance in effecting a distribution of the pressure and in enabling the presser to adapt itself to inequalities in the material being pressed. Furthermore, the presser is molded to correspond to the shape and size of the average shoe of a given range of sizes or styles and is able by its resilient and yielding characteristics to conform to and hug closely shoes having varying sizes and contours of the forepart.

Another feature of the invention relates to the means for attaching the welt presser to its supporting member so that a predetermined pressure may be applied through it to the welt. Sole laying machines as usually constructed are provided with a standard adjustably mounted upon a cross-head which carries a cushioned block for engaging the forepart of a shoe to support the same in opposition to the pressure exerted upon the bottom of the shoe by the sole laying pad. In an embodiment of this feature of my invention a collar is mounted upon the said standard and arranged to be resiliently depressed, and means is provided for varying the tension of the resilient means so as to apply a predetermined pressure to the welt. Arms extend outwardly and downwardly from the collar to provide supports for the welt presser at a plurality of points. In practice and as illustrated one arm extends to the toe portion of the presser and one to each side of the shoe to engage portions of the presser opposite the ball or instep of the shoe. This arrangement of the presser supports embodies another important feature of the invention: namely, that the work presser is more firmly supported at the points where it engages those portions of the welt having the greatest curvature, that is, at the toe and ball portions, where the tendency of the welt to separate from the sole is consequently greatest, as previously explained, it being highly important that the means for applying pressure to the welt should be especially effective at the toe and ball portions.

Another feature of the invention consists in the provision of novel means for adapting a single presser to shoes of a variety of widths and sizes. In the illustrated machine the arms which are attached to the welt presser along the sides of the shoe have provision for movement or adjustment of the presser relatively to them. Preferably this provision for adjustment may take the form of stud and slot connections between the arms and presser, and as shown slots are formed in the presser and are provided with suitable bushings, preferably corru-

gated to hold firmly in the material of the presser, for the reception of stud screws which pass through the bushings and are threaded into the presser support to which the presser is clamped by tightening the screws.

The construction of the welt presser of a continuous strip of resilient material embodies another feature of the invention. The workman in presenting the work in the machine holds the rear portion of the last upon the heel support and forces the forepart of the shoe into the band which is set, by the adjustment referred to, tightly enough so that the weight of the shoe will be sustained as it is brought down against the sole laying pad. The resiliency of the band enables it to conform to the different shape and swing of the foreparts of shoes and to limited variations in size without change of adjustment; and the frictional engagement of the band with the shoe, in spite of these variations, is sufficient to sustain the shoe until supported by the sole pad.

As a further feature of the invention the welt presser is so constructed as to be more easily flexed at the points where the amount of vertical flexure is greatest, as at the point where the welt turns from the ball portion into the shank portion and at the corners of the toe.

An important feature of this invention consists in novel means for holding the welt during the sole laying operation. In the illustrated embodiment of the invention the welt holding means comprises a resiliently supported flexible member which is preferably arranged to embrace the forepart of the shoe.

A further feature of the invention consists in a novel combination of welt holding means with a toe block. As herein shown a toe block is arranged to hold the forepart of the shoe against the upward pressure of the sole laying pad, and the welt holder is resiliently movable relatively to the block. Preferably the welt holder is yieldingly held in such relation to the toe block that the holder clamps the welt and the margin of the shoe sole against the sole pad before the toe block clamps the last and the body of the sole against the sole pad. For this purpose the welt holder is mounted on the toe block support for movement upwardly against spring pressure which can be predetermined by adjustments.

Another feature of the invention consists in a welt holder comprising continuous, flexible means. In the illustrated embodiment of the invention a thick flexible rubber band is arranged to embrace the forepart of the shoe and bear upon the top face of the welt. Frictional engagement of the band with the forepart of the shoe may be utilized to assist in holding the forepart

of the shoe while the shoe is carried into engagement with the sole pad.

These and other features of the invention will appear more fully from the following 5 detailed description in connection with the accompanying drawings, and will be defined in the appended claims.

Figure 1 is a side view of a portion of a sole laying machine with an illustrative embodiment of my invention applied thereto; and Fig. 2 is a detail in perspective of an 10 end portion of the welt presser.

As illustrated, the shoe supporting jack is secured to a cross-head 2 which is mounted 15 to reciprocate on vertical guide rods 4. The cross-head is supported upon springs 6 surrounding the guide rods and is depressed to bring the sole of the shoe into contact with the presser pad 8 by means of a 20 treadle (not shown) connected by rods 10 to the cross-head. Clutch collars 12 are mounted to reciprocate upon the guide rods 4 above the cross-head 2 and act to lock the cross-head 2 in its depressed position 25 during the upward movement of the presser pad 8 to press the sole into position upon the shoe.

A rock-shaft 14 is mounted in the cross-head 2 and carries arms 16 which are connected by links 18 with levers 20 pivoted at 30 22 and having upwardly directed ends 24 adapted to engage the clutch collars 12, it being understood that these parts are duplicated upon the opposite side of the machine. 35 The rock-shaft 14 also carries a handle 26 by operation of which, through the system of levers described, the clutch collars 12 may be raised so as to release them from the guide rods 4 and allow the spring 6 surrounding the guide rods to raise the cross-head 2 and the clutch collars to their initial 40 position.

The jack comprises as usual a depending last pin, not shown, and a rest provided 45 with a cushion 30 to engage the top face of the forepart of the shoe.

For a fuller description of the mechanism above briefly described, reference may be had to the patents previously mentioned.

50 The cushioned block 30 which holds the toe portion of the shoe against the action of the presser pad 8 is pivoted at 32, upon an axis extending longitudinally of the shoe, to a block 34 which is pivoted, upon an axis 55 extending at right angles to the axis 32, to a member 35 secured to the post 36 which is fixed to a block 38 mounted to slide for adjustment on the T-guide 40 of the cross-head 2. Upon the post 36 is mounted for 60 sliding movement a collar 42 carrying the arms 44 and 46 which extend outwardly and downwardly therefrom toward the plane of the shoe bottom. The post 36 is provided with a keyway 50 and a screw 52 65 is threaded through the collar 42 into en-

gagement with the keyway 50 to limit rotation of the collar 42 upon the post 36. The lower ends of the arms 44 and 46 carry the presser member 56 which, in the operation of the machine, is adapted to rest against 70 the upper side of the welt of a welt shoe or the sole attaching flange of any other kind of shoe.

To provide the requisite pressure of the presser upon the welt during the sole laying operation, a spring 60 is provided which surrounds the post 36 and rests upon the upper side of the collar 42. The other end of the spring rests against the nut 62 which is threaded upon the post 36 and provides means for adjusting the tension of the spring 60. The initial position of the welt presser as the shoe is brought into engagement with it is somewhat below the normal position of the welt relatively to the toe block 30, and as the jack is brought down by the operation of the treadle through the rods 10 into position with the shoe resting upon the pad 8 and the pad is raised, the welt presser 56 first applies pressure to the 85 welt, and as the pressure of the presser upon the welt increases by reason of the upward movement of the pad 8 the presser yields to permit the toe of the shoe to come in contact with the block 30 the collar 42 90 sliding upwardly upon the post 36 and compressing the spring 60.

95 The presser member 56 is preferably made of some such material as soft rubber and may, if found desirable, be strengthened by 100 a backing of metal or other suitable material 70 placed upon the top thereof. The welt presser is provided with holes or slots for attaching it to the arms 44, 46 of the support. The arms have flanges 72 against 105 which the presser or its backing may rest and stud-screws 74 are passed upwardly through the holes in the presser and are threaded into the arms, the heads of the screws being sufficiently large to bear 110 against the presser member and hold it in position upon the arms. The holes of the presser member where it is attached to the side arms 46 are preferably elongated as 115 shown in Fig. 2 and provided with bushings 76 so that the side portions of the presser may be adjusted laterally of the shoe relatively to the arms 46 by loosening the screws 74. The hole in the toe portion of the presser is also preferably provided with a 120 bushing and the bushings are all externally roughened or corrugated to afford a secure hold upon the material of the presser.

125 It will be noted that where the side arms are attached to the presser member a portion of the material of the presser is removed as at 78, Fig. 2, so that these portions of the presser are more flexible than its other portions. From Fig. 1 it will be seen 130 that this portion of the presser operates

upon the welt at the point of its greatest upward curvature from the ball toward the shank.

In the operation of the machine a shoe is placed upon the heel pin (not shown), and the forepart of the shoe swung into place beneath the cushioned toe block 30 and into the embrace of the welt presser which, as the shoe is forced upwardly against the block 30, applies initial pressure downwardly upon the welt, the sole of the shoe meantime being pressed up against the bottom of the shoe by the hands of the operator and held thereby cement. By depression of a treadle the cross-head 2, which is initially in an elevated position, is brought down to bring the sole and shoe against the pad 8, further pressure against which elevates the presser. The treadle may now be released whereupon the clutch collars 12 act to grip the rods 4 and prevent upward movement of the cross-head 2. Power is now applied to force upwardly the pad 8 and apply pressure uniformly over the entire bottom of the sole, the pressure of the presser member 56 against the welt and outstanding margin of the outsole serving to maintain these parts in intimate contact with each other during the sole laying operation and until after the cement which has been applied between the engaging surfaces has caused them firmly to adhere.

Having described my invention, what I claim as new and desire to secure by Letters Patent of the United States is:—

1. In a machine of the class described, the combination with means for applying pressure to the outsole of a shoe, of resiliently supported means comprising a flexible member which engages the welt of the shoe in opposition to the action of the pressure applying means upon the margin of the outsole.

2. In a machine of the class described, the combination with means for applying pressure to the outsole of a shoe, of a member composed of resilient material arranged to embrace the forepart of the shoe and means for holding the embracing member in position and applying an opposing pressure to the welt of the shoe.

3. A sole laying machine, having in combination, a pad for engaging the sole, a toe block for opposing the pressure of the sole pad and a welt presser arranged to bear upon the welt, the presser being resiliently movable relatively to the toe block in a direction to oppose the pressure exerted by the sole pad upon the margin of the sole.

60 4. A sole laying machine, having in combination, a pad for engaging the sole, a toe block for opposing the pressure of the sole pad and a welt presser arranged to contact with the welt and apply pressure resiliently

thereto prior to the contact of the toe block with the shoe.

5. In a sole laying machine the combination with a toe block, a toe block support, a sole pad and means for relatively moving the said pad and block to apply pressure to the sole, of a welt presser, a support for the presser mounted for movement upon the toe block support, and a spring for normally depressing the presser below the plane of the sole of the shoe in contact with said toe block.

6. In a sole laying machine the combination with a toe block, of a toe block support, a sole pad and means for relatively moving the said pad and block to apply pressure to the shoe, a collar slidably mounted upon said toe block support, arms extending downwardly from said collar outside the lines of the toe and sides of the shoe, and a welt presser carried on said arms and arranged to contact with the welt about the forepart of the shoe.

7. In a sole laying machine the combination with means for applying pressure to the outsole of a shoe, of flexible means for applying opposing pressure to the welt of the shoe, said welt pressing means having the greater flexibility at the points where the amount of flexure of said means when in operation is greatest.

8. A machine of the class described, having in combination, a band formed of a continuous piece of material arranged to embrace the forepart of a shoe and to bear upon the outstanding sole attaching flange, said band being mounted for vertical bodily movement, and means for pressing the band against the welt.

9. A machine of the class described, having in combination, means for holding a last with a welted shoe on it, means for applying pressure to the shoe bottom, resiliently supported means for applying pressure to the outstanding margin of the welt in opposition to that applied to the under side of the outstanding margin of the outsole and means for thereafter applying pressure externally over the forepart of the shoe.

10. A machine of the class described, having in combination, means for supporting the toe portion of a shoe, said shoe having a marginally projecting portion, means for applying pressure to the shoe bottom, and means for applying predetermined pressure to said marginally projecting portion in opposition to that applied to the outstanding margin of the sole.

11. A machine of the class described, having in combination, means for supporting a lasted welt shoe at the forepart thereof, means for applying sole laying pressure to the bottom of the shoe, and continuous, flexible means acting upon the welt in op-

- position to the sole laying pressure upon the shoe bottom to secure adhesion of the outstanding margin of the welt to the outer margin of the outsole.
- 5 12. A machine of the class described, having in combination, means for supporting a shoe which has an outstanding sole attaching flange, means for supporting the outer margin of the sole adjacent to said flange, 10 and means for forcing the flange into contact with said margin to cause adhesion of the cemented contacting surfaces, said means being constructed to apply automatically the firmest pressure at the portions of the 15 flange extending about the parts of the periphery of the shoe having the greatest curvature.
13. A machine of the class described, having in combination, means for supporting the forepart of a shoe, continuous means extending about said forepart adapted to engage the welt, means for pressing the welt engaging means resiliently toward the sole, and means for pressing the sole against the 25 shoe.
14. A machine of the class described, having in combination, means for supporting the forepart of a shoe, means for applying pressure to the outer face of the sole in opposition to said supporting means, and means engaging the welt constructed and arranged to apply automatically the greatest welt flattening pressure at the points where the welt has the greatest tendency to 35 curl away from the sole.
15. A machine of the class described, having in combination, a sole laying pad, a toe block and support therefor, and resilient means carried by the toe block support and 40 shaped to receive and hold the forepart of a shoe prior to its engagement with the sole laying pad and to apply pressure to the welt during the sole laying operation.
16. In a machine of the class described, a 45 sole laying pad, a toe block, and flexible means for embracing the forepart of the shoe and holding the same frictionally in position to engage the sole laying pad for the sole laying operation.
17. In a machine of the class described, 50 the combination with suitable supporting means, of a presser for the outwardly extending margin of the upper of the shoe, said presser being composed of resilient non-metallic material and having elongated 55 bushings therein, and screw studs extending through the bushings and threaded into the support whereby the presser is adjustably clamped to its support.
18. In a machine of the class described, 60 the combination with suitable supporting mechanism, of a presser for the outwardly extending margin of the upper material of a shoe, said presser being composed of resilient non-metallic material and shaped to 65 conform to the periphery of the forepart of an average shoe whereby it is able to conform to varying contours and sizes and to hug closely the shoe.
19. A sole laying machine, having in combination, a pad for engaging the sole, a toe block for opposing the pressure of the sole pad, and means to engage and turn down a curled up welt around the toe prior to the application of sole laying pressure to the 75 shoe and sole.
20. In a sole laying machine, a sole laying pad, a toe block, and a thick flexible rubber band constructed and arranged to embrace the forepart of a shoe and engage the top 80 face of the welt during the sole laying operation.
21. In a sole laying machine, a sole laying pad, a toe block, means constructed and arranged to embrace the forepart of a shoe 85 and engage the top face of the welt, and means for holding the welt engaging means yieldingly depressed relatively to the toe block into position to engage the welt before the block engages the toe. 90

In testimony whereof I have signed my name to this specification in the presence of two subscribing witnesses.

JAMES CAVANAGH.

Witnesses:

EVERETT W. VARNEY,
JAMES R. HODDER.

It is hereby certified that in Letters Patent No. 1,161,843, granted November 30, 1915, upon the application of James Cavanagh, of Boston, Massachusetts, for an improvement in "Welt-Laying Machines," errors appear in the printed specification requiring correction as follows: Cancel all matter from line 34, page 1, to and including line 96, page 2; page 3, line 7, after the period insert the words *In the drawings.;* and that the said Letters Patent should be read with these corrections therein that the same may conform to the record of the case in the Patent Office.

Signed and sealed this 18th day of April, A. D., 1916.
